(57) **CLAIM**

The ornamental design for a transmitter for a pet trainer, as shown and described.

DESCRIPTION

FIG. 1 is a perspective view showing our new design for a transmitter for a pet trainer, in a first embodiment, and taken from a right rear angle.

FIG. 2 is a right side elevational view thereof.

FIG. 3 is a left side elevational view thereof.

FIG. 4 is a top view thereof.

FIG. 5 is a bottom view thereof.

FIG. 6 is a front elevational view thereof.

FIG. 7 is a back elevational view thereof.

FIG. 8 is a perspective view showing our new design for a transmitter for a pet trainer, in a second embodiment, and also taken from a right rear angle.

FIG. 9 is a right side elevational view thereof.

FIG. 10 is a left side elevational view thereof.

FIG. 11 is a top view thereof.

FIG. 12 is a bottom view thereof.

FIG. 13 is a front elevational view thereof.

FIG. 14 is a back elevational view thereof.

FIG. 15 is a perspective view showing our new design for a transmitter for a pet trainer, in a third embodiment, and also taken from a right rear angle.

FIG. 16 is a right side elevational view thereof.

FIG. 17 is a left side elevational view thereof.

FIG. 18 is a top view thereof.

FIG. 19 is a bottom view thereof.

FIG. 20 is a front elevational view thereof; and,

FIG. 21 is a back elevational view thereof.

The structural features shown in broken lines have been shown for the purpose of illustrating portions of the transmitter for a pet trainer that form no part of the claimed design.
